UNITED STATES PATENT OFFICE.

DANIEL SABO, OF BRIDGEPORT, CONNECTICUT, ASSIGNOR OF ONE-HALF TO MICHAEL KOCEZ, OF BRIDGEPORT, CONNECTICUT.

LIFE-PRESERVING SUIT.

1,146,250.

Specification of Letters Patent. Patented July 13, 1915.

Application filed October 7, 1914. Serial No. 365,455.

To all whom it may concern:

Be it known that I, DANIEL SABO, a subject of the King of Hungary, and resident of Bridgeport, in the county of Fairfield and State of Connecticut, have invented certain new and useful Improvements in Life-Preserving Suits, of which the following is a specification.

My invention relates to new and useful improvements in life preserving suits.

The object of the invention is to provide a suit which may be worn over an ordinary suit of clothing and which can be quickly put on and adjusted and especially to provide a suit which when applied as above suggested will hold a person in and upon the water, and so that the upper portion of the body and head will be supported above the surface; further to provide around the body portion of the suit an annular pneumatic compartment and which when inflated with air serves as the means for supporting the suit and person contained therein upon the water; further to provide connections with the said pneumatic compartment whereby the same may be conveniently filled and replenished with air as occasion may require by a hand operation of the wearer and finally to design the suit so that the same may be made perfectly tight, safe, and durable besides inexpensive to manufacture.

With these and other objects in view the invention resides and consists in the construction and novel combination and arrangement of parts hereinafter more fully described, illustrated in the accompanying drawings, and pointed out in the claim hereto appended, it being understood that various changes in the form, proportion, size and minor details of construction within the scope of the claim may be resorted to without departure from the spirit or sacrificing any of the advantages of the invention.

Similar characters of reference denote like or corresponding parts throughout the several figures of the accompanying drawings forming a part of this specification and upon which—

Figure 1 shows a sectional elevation of my improved suit complete and as the same appears when worn by a person and inflated and ready for use, and, Fig. 2 is a side elevation of the device shown in Fig. 1.

As will be noted the complete device is formed in two parts, though I make claim at this time to the body portion only and have illustrated the hood portion only to show the completeness of the outfit. 60

The suit is obviously formed of rubber or a suitable rubber cloth preparation which will serve to prevent the leakage of water and likewise to prevent the escape of air from the pneumatic compartment. The suit includes a body portion 5 formed of one piece and having leg and arm extensions 6 and 7. The open neck portion 8 is gathered and provided with a cord 9 by means of which it may be closed around and 70 against the neck of the wearer.

10 represents an annular pneumatic chamber which extends around the body portion of the suit and is adapted to be inflated by a bellows 11 or other suitable air pumping device which is secured to the upper body portion of the suit and is connected by a flexible tube 12 with the pneumatic chamber so that by the operation of the hand or arm air may be readily forced into the chamber. 75 This pipe is preferably rigidly connected to the suit and thus forms a permanent part of the outfit. The pneumatic compartment is preferably made of a size proportionate to that shown in the drawing and obviously 80 ample to support most any size person. 85

The hood 14 is preferably secured to the back of the body of the suit in the form of a cape and rests upon the head of the wearer with the front edge or flaps lying loose upon the chest of the body portion of the suit. Suitable pieces of glass 15 are inserted in front of the hood to permit the wearer to see out and a piece of metal or wire gauze 16 is also inserted so as to permit the wearer 95 to breath easily.

Having thus described my invention what I claim and desire to secure by Letters Patent is:—

A life preserving suit of the class described, the same comprising an integral body portion formed of water tight material and including arm and leg extensions having attached gloves and feet and having a closed front and back and an open upper 100 end portion, means for closing the said opening together against the neck of the wearer, an integral annular pneumatic compartment extending entirely around the outside of the body portion of the suit the inner 105 110

wall of the compartment forming the wall
of the suit, an air inflating device attached
to the upper portion of the suit and beneath
one arm, and connections from the inflating
5 device to the air compartment for filling
the same with air.

Signed at Bridgeport, in the county of

Fairfield and State of Connecticut, this 3rd
day of October A. D., 1914.

DANIEL X SABO.
